Fig. 3

Fig. 4

Fig. 5

FIG. 1 is a front elevation of a votive lighting fixture showing my new design, with the standard shown broken away in part to indicate intermediate length;

FIG. 2 is a rear elevation thereof with the standard fragmentarily shown for convenience of illustration;

FIG. 3 is a side elevation thereof as shown in FIG. 2;

FIG. 4 is a top plan view thereof; and

FIG. 5 is a bottom plan view thereof.

The side of the votive lighting fixture not shown is a mirror image of the side shown.

The dominant features of my design reside in the full line portions of the drawing.

I claim:

The ornamental design for a votive lighting fixture, substantially as shown and described.
